UNITED STATES. PATENT OFFICE.

MANUEL A. BLUM, OF CHICAGO, ILLINOIS.

LAST.

Application filed January 5, 1924. Serial No. 684,568.

To all whom it may concern:

Be it known that MANUEL A. BLUM, a citizen of the United States, residing at Chicago, in the county of Cook and State of Illinois, has invented new and useful Improvements in Lasts, of which the following is a specification.

The present invention relates to lasts for boots and shoes, and more particularly to the type of last which is divided to form several relatively movable parts, whereby the last may be collapsed to facilitate its removal from the shoe.

An object of the invention is to provide a construction which will permit the application of the last to the shoe and its removal therefrom without breaking the upper or imposing upon the seams, strains tending to displace the same and to misshape the shoe.

Further objects of the invention are to provide a last which, by reason of its construction, may be cheaply manufactured and readily operated; to afford a locking means which will retain the parts in their proper relative positions when the last is in use, and further to provide a single means for collapsing and expanding the last which will serve to vary both the length and width of the last when actuated.

Other objects of the invention will become apparent as the description proceeds in connection with the embodiment of the invention disclosed in the accompanying drawings wherein:

Figure 1 is a side elevational view.

Figure 2 is a top plan view.

Figure 3 is a longitudinal section on the line 3—3 of Figure 2.

Figure 4 is a view showing certain sections of the fore part relatively displaced and with a side section of the fore part removed in order to clearly disclose the interior construction.

Figure 5 is a side elevational view showing the relative position of the parts of the last when the same is partially collapsed and is about to be removed from or inserted into a shoe.

Figure 6 is a sectional view on the line 6—6 of Figure 1, and

Figure 7 is a sectional view on the line 7—7 of Figure 1.

Referring to the drawings for a more detailed description, the last is of a type comprising a fore part 10, a heel or counter part 11, and an expanding part 12 interposed be-

tween the heel and fore part. These parts may be made of wood, metal or suitable fibrous material.

The fore part is preferably collapsible, or, in other words, transversely contractible and expandable to facilitate its insertion into and removed from a shoe. It should also be constructed so that when set up, the surface is substantially unbroken to provide a continuous supporting surface for the shoe. In order to obtain this lateral expansion, any desirable arrangement of parts may be employed, the construction shown in the drawings having been found to be particularly useful and comprising side sections 13, 14 separated by an intermediate wedge section 15. The side sections are connected to the wedge section 15 by means of a cross pin 17 (Figure 7) extending through an opening 18 in the center section and having upturned ends 17' fitting into longitudinal slots or grooves 19. The grooves are partially closed by means of metallic strips 20 secured at their ends to the face of the side sections, as by means of screws 21, (Figure 4) and extending downwardly over the upper edge of the grooves whereby they serve to engage the upturned end 17' of the cross pins 17 and prevent the separation of the several sections of the last fore part. As will be noted in Figure 4, the central section and the two side sections are relatively movable longitudinally of the last. In order to guide the sections in this sliding movement, which serves to vary the length of the last, the central section has on each side face thereof a key or rib 22 which fits into the registering groove 19 and thereby retains the sections in the same horizontal plane as the center section is moved forwardly and rearwardly.

It will be understood, of course, that the particular means employed for collapsing and expanding the last fore part may be modified without departing from the invention. The preferred means, however, comprises a wedge, such as the section 15, serving to move the two additional sections, such as the side sections 13 and 14 relative to one another transversely of the last.

The lateral expansion of the last, as well as the longitudinal expansion of the same, to vary the last length, are preferably accomplished by a common means, which, in the present instance, is the intermediate expanding member 12. It will be noted that the

forward face 25 of the heel part and the rear end surface 26 of the fore part, particularly of the central section thereof, slightly converge downwardly and the engaging surfaces of the intermediate part 12 are similarly inclined so that the latter serves as a wedge when interposed between the fore part and the heel part. The insertion of the expanding part 12 between the heel part to the fore part serves to separate the two last mentioned parts and to increase the length of the last. Likewise its withdrawal permits the removal of the heel part from the shoe, thereby collapsing the last.

The specific construction of the expanding part 12 is important, although the invention is not limited to this precise detail. The expanding part comprises a lower portion 28 and an upper portion 29 pivoted thereto, in the present instance by means of side plates, 30, secured to the lower portion and having openings receiving pintles 31 extending into the upper portion and upon which the latter rocks. The upper portion carries on its top surface a pin 32 extending through a slot 33 in a locking plate 34, which is bifurcated at its forward end and provided with eyes 35, through which pass a pivot pin 35' secured to a plate 35'', the latter being affixed to the fore part. It will be understood that the two plates 34 and 37 constitute a leaf hinge, by means of which the fore part and the expanding part are pivotally connected. The plate 34 of the hinge is retained in engagement with the intermediate or expanding part 12 by means of the pin 32 extending through the slot 33 therein, the pin carrying a cap 40 preventing separation of the hinge and last part and permitting the latter to move relative to the hinge as it is inserted into and withdrawn from the last.

When the last is in use, the two portions of the expanding part are in the relative positions shown in Figures 1, 2 and 3, and for the purpose of facing the expanding part, as well as limiting the rocking movement of its top portion, facing plates 42 and 43 are provided, the edges of which abut when the part is positioned in the last.

To retain the parts of the last against displacement when the last is in use, a suitable locking means is provided. In the preferred construction, the hinge plate 34 is extended rearwardly so that its end portion 34' fits beneath a leaf spring 36 secured at 37 in a pocket 38 formed in the heel part. The spring is formed with a horizontally extending terminal portion 36'', beneath which the plate 34 fits. The end is turned upwardly and rearwardly, as at 36''', so that the spring may be freely retracted to permit the expanding part to be withdrawn from the last from the position shown in

Figure 1 to the position shown in Figure 5. With the expanding part thus withdrawn, the heel part may be removed from the shoe. It will be noted that as the expander 12 is raised, the central section 15 of the fore part is retracted, thereby simultaneously varying the width of the last. This is an important feature of the invention, since the actuation of the expanding part produces two results, namely, the longitudinal collapsing of the last, that is, the reduction in length thereof, and also the variation in the last width.

The operation of the last is as follows: When the last is about to be inserted in a shoe, the sections of the fore part are arranged substantially as shown in Figure 5, and with the expanding part 12 fully withdrawn from the shoe. The counter or heel part is then inserted, and with the parts in this relative position, the last is approximately one-half inch shorter than its normal length and about one-quarter inch narrower in the vamp and toe, it being noted that the center or expanding section of the fore part 15 is slightly retracted. Such manufacturing operations as may be desirable before the expansion of the last, as, for instance, the placing of the seams in proper position, may then be readily performed on the shoe. The expanding or center part 12 of the last is then pressed downwardly, and in its continued movement from the position shown in Figure 5 will move the center section of the fore part forwardly; thus expanding the last both in length and in width. The rear end of the hinge plate 34 will snap beneath the leaf spring 36, thus locking the parts in their proper position.

When the last is to be collapsed, the center part 12 is raised to the position shown in Figure 5. As this part is raised, the two portions thereof will move relative to one another about the pivot pins 31 and the pin 32 will slide forwardly in the slot 33 of the hinge plate. This operation is accomplished without imposing any strain upon the shoe. When the expanding part is fully raised and withdrawn from the shoe, the heel part may be withdrawn from the shoe and subsequently the center portion of the fore part may be withdrawn by sliding it further rearwardly so that the sections of the fore part are in the relative position shown in Figure 4.

In order to retain the parts of the last together when the same is not in use, a substantially U-shaped clip 45 has its parallel arms 45' extending through openings in the heel part and registering openings in the several sections of the fore part. This clip serves as convenient means for maintaining the last assembled when not in use.

It should be understood that numerous modifications may be made in the structure

illustrated and described without departing from the invention.

I claim:

1. A divided last comprising a fore part, a heel part, and an expanding part interposed between the aforesaid parts and adapted to vary the length of the last, said fore part including means operable upon movement of said expanding part to vary the width of said fore part, the latter when expanded transversely having a substantially continuous unbroken surface in transverse planes.

2. A divided last comprising a fore part, a heel part, and an expanding part removably interposed between the aforesaid parts and adapted to vary the length of the last, said fore part including means operable upon insertion and withdrawal of said expanding part to vary the width of said fore part.

3. A divided last comprising a fore part, a heel part, and an interposed expanding part adapted to separate the aforesaid parts and thereby to vary the length of the last, said fore part having two sections relatively movable transversely of the last upon movement of said expanding part to vary the width as well as the length of the last.

4. A divided last comprising a fore part, a heel part, and an expanding part interposed between the aforesaid parts and adapted, upon insertion and withdrawal, to vary the length of the last, said fore part having two sections relatively movable transversely of the last upon insertion and withdrawal of the expanding part to vary the width of the last.

5. A divided last comprising a fore part, including two sections relatively movable transversely of the last to vary the width thereof, a heel part, and an expanding part interposed between the fore part and the heel part, and means operatively connected with said expanding part adapted to move the sections of the fore part when the expanding part is actuated, and to fill the surface space between said two sections of the fore part.

6. A divided last comprising a fore part, including two sections relatively movable transversely of the last to vary the width thereof, a heel part, and an expanding part removably interposed between the fore part and the heel part, and means operatively connected with said expanding parts to relatively move the sections of the fore part when the expanding part is inserted or withdrawn.

7. A divided last comprising a fore part, including two sections relatively movable transversely of the last to vary the width thereof, a heel part, and an expanding part interposed between the fore part and the heel part, and wedge means operatively con-

nected with said expanding part adapted to relatively move the sections of the fore part when the expanding part is actuated, said wedge means including a section for said fore part adapted to be positioned in the space between said two sections.

8. A divided last comprising a fore part, including two sections relatively movable transversely of the last to vary the width thereof, a heel part, and an expanding part removably interposed between the fore part and the heel part, and wedge means operatively connected with said expanding part to move the sections of the fore part when the expanding part is inserted or withdrawn.

9. A divided last comprising a fore part, transversely adjustable to vary the width thereof, a heel part, an expanding part interposed between the aforesaid parts and adapted by engagement therewith to vary the length of the last and to vary the width of the fore part, said fore part when expanded having a substantially continuous uninterrupted surface in transverse planes.

10. A divided last comprising a fore part, transversely adjustable to vary the width thereof, a heel part, an expanding part removably interposed between the aforesaid parts and adapted by engagement therewith to vary the length of the last and to vary the width of the fore part.

11. A divided last comprising a fore part, a heel part, said fore part being transversely adjustable to vary the width of the last and having when expanded a substantially uninterrupted surface, and a common means serving to vary the width of the last fore part and to vary the length of the last.

12. A divided last comprising a fore part, a heel part, said fore part being transversely adjustable to vary the width of the last, and a common means serving upon introduction into and withdrawal from the last to vary the width of the last fore part and to vary the length of the last.

13. A divided last comprising a fore part, including side sections, a central wedge section movable longitudinally of the last relative to said side sections and serving upon such movement to vary the width of said fore part, said wedge section being adapted to fill the space in the planes of the surface of the last fore part between the said sections when the latter are moved apart, a heel part, and an expanding part interposed between the heel part and the fore part, said expanding part being movable relative to said heel part to vary the length of the last and serving also to actuate said wedge member of the fore part to vary the width of the latter.

14. A divided last comprising a fore part including side sections and a central section movable longitudinally of the last relative to said side sections, said wedge section be-

ing adapted to fill the space in the planes of the surface of the last fore part between the said sections when the latter are moved apart, means on said sections for guiding the central section in its movement, said central section serving as a wedge means to vary the width of said fore part when moved relative to said side sections.

15. A divided last comprising a fore part 10 including a plurality of longitudinal sections relatively movable longitudinally of the last, a heel part, an expanding part adapted to be interposed between said heel part and said fore part, said expanding part 15 being connected to one of said fore part sections, and said section being movable by said expanding part and when moved, serving to vary the width of said fore part, said fore part sections forming together a 20 substantially uninterrupted fore part surface when the fore part is transversely expanded.

16. A divided last comprising a heel part, a fore part, and a wedge shaped expanding 25 part adapted to be interposed between the aforesaid parts, said expanding part being pivotally connected to the fore part; a projection on said expanding part and a catch on the heel part adapted to be engaged by 30 said projection when the expanding part is moved into operative position and serving to hold the expanding part in such position.

17. A divided last comprising a heel part, a fore part, and a wedge shaped expanding part adapted to be interposed between the aforesaid parts; said expanding part being pivotally connected to the fore part, a projection on said expanding part and a spring catch on the heel part adapted to be engaged by said projection when the expanding part 40 is moved into operative position and serving to hold the expanding part in such position:

18. A divided last comprising a fore part, a heel part, an expanding part removably interposed between the aforesaid parts and adapted to vary the length of the last, said fore part including means operable upon insertion and withdrawal of said expanding part to vary the width of said fore part, and means for locking said expanding part in position when inserted in the last.

19. A divided last comprising a fore part, transversely adjustable to vary the width thereof, a heel part, an expanding part removably interposed between the aforesaid parts and adapted by engagement therewith to vary the length of the last and to vary the width of the fore part, and means for locking the expanding part in position when inserted in the last.

In testimony whereof I have hereunto set my hand.

MANUEL A. BLUM.
